UNITED STATES PATENT OFFICE.

JOSEPH C. FORD, OF MADISON, WISCONSIN, ASSIGNOR TO FRENCH BATTERY & CARBON COMPANY, OF MADISON, WISCONSIN, A CORPORATION OF WISCONSIN.

HAND-LAMP.

1,358,368.

Specification of Letters Patent.

Patented Nov. 9, 1920.

Application filed June 26, 1919. Serial No. 306,765.

To all whom it may concern:

Be it known that I, JOSEPH C. FORD, a citizen of the United States, residing at Madison, in the county of Dane and State 5 of Wisconsin, have invented a new and useful Improvement in Hand-Lamps, of which the following is a specification.

This invention relates particularly to electric hand-lamps; and the primary object is 10 to provide an improved lamp of this character which is inexpensive, and in which provision is made, in a very simple manner, for preventing accidental short-circuiting of the device.

15 The invention is illustrated, in its preferred embodiment, in the accompanying drawing, which represents a longitudinal sectional view, the batteries employed being shown in elevation, however.

20 In the construction illustrated, A represents a tubular casing which may be of convenient size to be carried readily in the hand, or, if desired, in the pocket; B, a battery, here shown as comprising two dry cells B'

25 and B²; C, a metallic reflector insulatingly mounted in one end of the casing; C', a lens surmounting said reflector; D, an incandescent lamp mounted in the reflector; and E, a contact-controlling device mounted on

30 one side of the casing near the front end thereof, and serving to control the position of a contact member E' which is adapted to make contact with the metallic reflector C, and which preferably is formed integrally with a resilient copper strip E² which leads 35 to the base end of the casing.

The casing A comprises a tubular body of insulating material, such as fiber, which is equipped at its base end with a threaded 40 sleeve, or ferrule, 1, upon which is screwed

a metal cap 2, which supports a conical metal spring 3; and a threaded metal sleeve, or ferrule, 4, which is secured on the front end of the tubular member A and has 45

screwed thereon a retainer sleeve, or ring, 5 which serves to clamp the reflector and lens in position.

As indicated, the reflector is of metal. It is provided with a socket 6 for the lamp D.

50 The cell B of the battery has the naked bottom of its zinc casing resting on and forming contact with the spring 3, and thus is in electrical connection with the base end

extremity of the conductor E² which is in permanent contact with the metallic sleeve 55

1. The cells are provided with central contacts 7. The naked zinc bottom of the upper cell bears against the central contact of the lower cell. The central contact of the lamp bears against the central contact of the adjacent cell, and the metallic shell of the socket-portion of the lamp is, of course, in contact with the metallic reflector C, which supports the lamp. Thus, the circuit of the device will be closed when the contact member 60 E' is moved into contact with the reflector. 65

The circuit is controlled by the device E. This comprises a guard 8 which is provided with a slot in which is mounted a sliding 70 button 9 equipped with a resilient shoe 10. The member 10 has an inclined portion 10^a adapted to work against a shoulder 11 at the upper end of a slot 11^a in the casing A. The cam-portion 10^a is provided with a slot 75 which engages a cam-portion 12 of the contact member E'. The arrangement is such that when the button 9 is shoved forwardly, the cam-portion 10^a will engage the shoulder 11 and force the contact member E' into 80 engagement with the reflector, thus completing the circuit. When the button is retracted, the spring contact member will move away, or be drawn away, from the reflector. The construction and arrangement are such 85 that the spring pressure will create sufficient friction to cause the button 9 to remain in any position in which it is placed. Thus, it will maintain the circuit in closed condition when set in the forward position, and 90 will maintain the circuit in open condition when placed in the retracted position shown in the drawing.

Inasmuch as the reflector is insulated from the metallic sleeves 4 and 5, it is evident 95 that the device cannot be short-circuited by laying the hand-lamp on a metallic surface.

The guard 8 is shown secured at its forward end to the casing A and the sleeve 4 100 by a rivet 13. At its rear end a guard is secured to the casing and to the resilient conductor E² by a rivet 13^a. By virtue of the arrangement shown, a single conductor, in the form of a resilient strip of copper, 105 for instance, may serve as a contact member

and as a conductor affording a continuous lead from the reflector to the base end of the hand-lamp.

The construction described is exceedingly simple, inexpensive, and thoroughly adapted to its purpose.

The foregoing detailed description has been given for clearness of understanding, and no unnecessary limitation should be understood therefrom, but the appended claims should be construed as broadly as permissible, in view of the prior art.

What I regard as new, and desire to secure by Letters Patent, is:

1. In a hand-lamp, the combination of an insulating casing, a closure for the base end thereof, a battery in said casing, an integral internal conductor in electrical connection with the base end of the battery and leading to the forward end of the casing where it is equipped with a contact member, a metallic reflector insulatingly mounted in the front end of the casing opposite said base end, said contact-member being adapted to contact with said reflector, a lamp mounted in said reflector and having central contact with the battery, a lens surmounting said

reflector, a sleeve securing said lens in position, and a sliding cam-device mounted on the casing near its forward end and adapted to actuate said contact member of said conductor, whereby the circuit may be established, or broken, at will.

2. In a hand-lamp, the combination of an insulating casing, a closure for the base end thereof, a battery in said casing, a resilient metal strip having electric connection with the base end of the battery and serving as an internal conductor leading to the forward end of the casing, where it is provided with a contact member having a cam-portion, a slide mounted on the forward end of the casing and engaging the cam-portion of said contact member, a metallic reflector insulatingly mounted in the forward end of the casing, said contact-member being adapted to make contact with said reflector, a lamp mounted in said reflector and having central contact with the battery, a lens surmounting said reflector and disposed adjacent to said contact member, and a sleeve securing said reflector and lens in position.

JOSEPH C. FORD.
